UNITED STATES PATENT OFFICE.

BENJAMIN LE VINO, OF NEW YORK, N. Y.

DESIGN FOR A BASE AND CASING FOR PORTABLE TELEPHONES, &c.

SPECIFICATION forming part of Design No. 30,794, dated May 16, 1899.

Application filed December 28, 1898. Serial No. 700,569. Term of patent 7 years.

To all whom it may concern:

Be it known that I, BENJAMIN LE VINO, a citizen of the United States, residing at New York, in the State of New York, have invented and produced a new and original Design for a Base and Casing for a Portable Telephone and Switchboard, of which the following is a specification, reference being had to the accompanying drawings, which show the design.

The design will be best understood by the drawings.

It consists in the general shape and relation of the parts.

B is the hole for the switch-arm central in the face of the switch-connection casing D. Exposed on the face of the casing are the concentric series of contacts C and the push-button recess C'. In the periphery of the case, at one side, is the receiver-slot F. The case D is mounted, as shown, above the massive base or pedestal G. The mouthpiece or transmitter post H rises above the case D, so as to give the graceful outline and appearance shown in the drawings.

What I claim is—

The design for a base and casing for a portable telephone and switchboard, herein shown and described.

In testimony whereof I have hereunto set my hand, at New York, this 19th day of December, 1898.

BENJAMIN LE VINO.
